UNITED STATES PATENT OFFICE.

WILHELM BECKER, OF NEW YORK, N. Y.

DESIGN FOR A WATCHCASE.

Application filed March 21, 1927. Serial No. 21,227. Term of patent 3½ years.

hom it may concern:

known that I, WILHELM BECKER, a f Germany, residing at New York, ounty of New York and State of rk, have invented a new, original, umental Design for Watchcases, of e following is a specification, refer-ing had to the accompanying draw-ning part thereof.

1, is a face view of a watch case,
my new design.

Figure 2, is a perspective view of my new design with the face ornamentation shown in Figure 1 omitted, for the purpose, of showing contour.

I claim:

The ornamental design for a watchcase, as shown, and described.

WILHELM BECKER.
